CLAIM

The ornamental design for a blister package for analyte test strip, as shown and described.

DESCRIPTION

FIG. 1 is a top front perspective view from above of our new ornamental design for a blister package for analyte test strip with the analyte test strip illustrated in dotted lines, which does not form a portion of the design;

FIG. 2 is a top plan view of our package design of FIG. 1; FIG. 3 is a bottom plan view of our package design of FIG. 1;

FIG. 4 is a front elevation view of our package design of FIG. 1;

FIG. 5 is a rear elevation view of our package design of FIG. 1; and,

FIG. 6 is a side elevation view of our package design of FIG. 1 with the other side being the same view.
